Primary Examiner — Samantha Q Lawrence(74) *Attorney, Agent, or Firm* — Siritzky Law, PLLC(57) **CLAIM**

I claim the ornamental design for a cover for electronic systems, as shown and described.

DESCRIPTION

FIG. 1 is a perspective view of a cover for electronic systems showing my new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 shows the cover for electronic systems on a pole. The utility pole shown in broken lines in FIGS. 1-9 illustrates environment of the cover for electronic system that forms no part of the claimed design. All of the broken lines in FIGS. 1-9, except for those showing the utility pole, illustrate portions of the cover for electronic system that form no part of the claimed design. Additionally, the horizontal broken line groupings that surround the cover for electronic system are boundary lines.

Examples of a cover for electronic systems with which the claimed designs may be used are a cover for an antenna system (such as a cellular antenna system) and the like on a pole (such as a utility pole) or the like. By way of example, the cover of the claimed designs may sit on or near the top of a utility pole and fully or partially cover a cellular antenna system mounted on the pole.

1 Claim, 9 Drawing Sheets(56)
